ATTACHING CLIP FOR ROOF GUTTERS

John A. Tobin, Philadelphia, Pa.

Application December 5, 1938, Serial No. 243,926

4 Claims. (Cl. 24—73)

The object of my invention is to provide an improved roof gutter. More especially, my device relates to an improved clip for attaching one edge of the gutter to the gutter hanger circle or other support.

More specifically, this improved clip consists of a resilient, semi-cylindrical portion adapted to engage the curved edge of the gutter, said clip having a perforation through it through which a portion of the gutter hanger circle extends, there being on the clip adjacent the lowest part of said perforation a curved wall adapted to embrace a portion of a gutter, hanger circle or other support adjacent that portion which passes through the perforation in the clip.

For a further exposition of my invention, reference may be had to the annexed drawing and specification at the end thereof my invention will be specifically pointed out and claimed.

20 In the drawing:

Fig. 1 is a side elevation with parts omitted and the gutter shown in vertical cross-section.

Fig. 2 is a rear elevation of the clip.

Fig. 3 shows the clip in perspective.

25 Fig. 4 is a side elevation showing a modification.

Fig. 5 is a side elevation showing a second modification.

In that embodiment of my invention chosen from among others for illustration in the drawing and description in the specification, my device is shown as consisting of a hanger 1 shown as a channel section having perforations 2 therein. Any means for attaching this hanger to the roof or other building structure may be employed and are not illustrated as they are well known. Supported on hanger 1 is a gutter hanger circle 3 having perforations 4 therein, some of which are arranged to register with the perforations 2 so that fastening means 5, shown as screws, pass through the perforations 2 and 4 which are in register and thereby secure the circle 3 to the hanger 1. At its outer end, circle 3 carries a hook 6 whose purpose will be more fully described; and, at its inner end, circle 3 carries a hook end 7 beneath which the inner edge 8 of the gutter 9 is adapted to be located. Gutter 9 has its outer edge 10 rolled, beaded or otherwise formed with a curved reinforcement.

50 There is provided a clip generally indicated at 11 for securing the outer edge of the gutter 9 to the outer end of the circle 3. Clip 11 includes a semi-cylindrical, curved portion indicated at 12 and adapted to be placed over the edge 10 of gutter 9 by being snapped thereon or placed

thereon in any other convenient manner. Through clip 11 extends a perforation 13 having a portion extending up into the semi-cylindrical portion 12 and a portion extending down into the depending portion 14 of clip 11. Adjacent the lower end of perforation 13 and formed from the walls of depending portion 14 there is provided a curved ridge or extension 15 of suitable shape, as seen in Fig. 1, to underlie the upper portion of hook 6 and to closely and elastically 10 or resiliently embrace the adjacent edge of circle 3. Clip 11 thus provides a resilient but firm and closely fitting means for attaching gutter 9 and gutter hanger circle 3 firmly together despite minor variations in the relative positions of these 15 parts.

In operation, the hanger 1 is secured to the building structure in any convenient location. Circle 3 is then attached to hanger 1 at a convenient height, depending upon the size of gutter 20 9 employed and other factors dictated by local conditions. Gutter 9 is then placed in the aligned circles 3 with its inner edge 8 beneath the hook 7. Clip 11 is then placed in a horizontal position and nose 15 slipped up under 25 hook 6. Clip 11 is then turned from the horizontal to a nearly vertical position so that the portion 12 snaps over the edge 10 of gutter 9, thus firmly holding gutter 9 and circle 3 together.

Fig. 4 shows a modification of my device in 30 which the clip 11 is provided at the rear or upper edge of the semicylindrical curved portion with a reversely bent flange or edge 16 which facilitates placing the clip over the rolled edge of the gutter.

Fig. 5 shows a second modification of my device in which the clip 11 is provided at the rear or upper edge of the semi-cylindrical curved portion with a roll or bead 17 which serves to reinforce the clip.

Although gutter or eaves trough 9 has been shown as of the square type, it may be of the curved semi-circular or semi-cylindrical type or of any other convenient configuration.

The clip 11 may be made from sheet metal, 45 strip or sheet steel, spring steel, copper, bronze or the like.

I do not intend to be limited save as the scope of the prior art and of the attached claims may require.

50 I claim:

1. A preformed, metal clip for attaching a gutter and a gutter hanger circle together, said clip comprising, a semicylindrical portion extending in circumference more than a half circle 55

and adapted to be snapped onto the gutter edge without permanent deformation, a dependent portion joined to said semicylindrical portion by a sharp bend providing a shoulder adapted to engage the lower side of a gutter, said clip having a perforation through both said portions large enough to permit the end of a gutter hanger circle to extend therethrough and to allow the clip to pivot on the gutter hanger circle when snapping into place, and a ridge beneath said perforation formed from said dependent portion and adapted to engage the adjacent edge of a gutter hanger circle.

2. A preformed, metal clip for use with roof gutters and gutter hanger circles comprising, a curved resilient portion adapted to snap over the edge of a gutter and to secure the clip to said gutter, a reversely bent projecting flange extending from one edge of said portion to guide the clip into proper engagement with the edge of said gutter, and a depending portion extending from the opposite edge of said curved resilient portion having a ridge extending out of the plane of the depending portion and adapted to embrace one edge of a gutter hanger circle.

3. A preformed, metal clip for use with roof gutters and gutter hanger circles comprising, a curved resilient portion adapted to snap over the edge of a gutter and to secure the clip to said gutter, a roll formed of the metal of said clip at one edge of said portion reversely bent to provide a reinforcement of said edge, and a depending portion extending from the opposite edge of said curved resilient portion and having a ridge extending out of the plane thereof and adapted to 10 embrace one edge of a gutter hanger circle. 5

4. A preformed, metal clip for use with roof gutters and gutter hanger circles comprising, a curved resilient portion adapted to snap over the edge of a gutter and to secure the clip to 15 said gutter, and a dependent portion joined to said curved resilient portion by a sharp bend providing a shoulder adapted to engage the lower side of a gutter, said clip having a perforation through both said portions large enough to permit the end of a gutter hanger circle to extend therethrough and to allow the clip to pivot on the gutter hanger circle when snapping into place. 20
